(57) **CLAIM**

The ornamental design for a tablet case, as shown and described.

DESCRIPTION

FIG. 1 is a front and right perspective view of a tablet case in a first open position.

FIG. 2 is a rear and left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front and left perspective view of the tablet case in a closed position;

FIG. 10 is a left view of the tablet case in a second open position;

FIG. 11 is a left view of the tablet case in a third open position; and,

FIG. 12 is a left view of the tablet case in a fourth open position.

The broken lines in the drawings illustrate portions of the tablet case that form no part of the claimed design. The broken line showing of a tablet in FIGS. 1-12 is for the purpose of depicting environmental subject matter only and forms no part of the claimed design.

1 Claim, 12 Drawing Sheets
